HEAT INTERCHANGING APPARATUS AND PROCESS

Application filed October 16, 1924, Serial No. 744,076, and in France March 19, 1924.

My invention has for its object a process for the exchange of heat between two fluids which are circulated continuously.

The process especially relates to the utilization of the calories carried by the products of combustion, but it is understood that the invention may also be applied to any process in which the calories are utilizable in the described manner.

It is known that the calorific exchanges take place under three forms: by conduction, by convection and by radiation and that in a temperature exchanger the calories carried by the heating fluid are divided into: calories retained by the cooled fluid, calories transferred to the heated fluid and calories dispersed by the external radiation of the apparatus. The first and third groups constitute the losses of the apparatus.

My process permits the reduction of these losses, thanks to my heat exchange device which utilizes simultaneously the three methods of heat transmission. The process consists in having the heating fluid circulated between a refractory body and a facing wall (or partition) which is refractory, conductive and of high radiative power, and the cold fluid circulated between said wall and a second refractory body which is not only refractory but of high radiative power. The heat of the heating fluid will be transmitted by convection to the refractory body and to the wall, and the heat of the refractory body will be transmitted by radiation

to the wall, while the heat received by the heated face will be transmitted by conduction—through the wall—to the heating face thereof. Furthermore, the heat of the wall will be transmitted by convection to the cold fluid by the said heating face and by radiation to the second refractory body, and the heat received by the second refractory body will be transmitted to the cold fluid by convection.

In order to obtain the optimal value of rapidity of exchanges it is necessary that all of the bodies mentioned have a high power of emission; it is also necessary that the wall be highly conductive, very thin and tight. It is then necessary that the distance

between the two refractory bodies and the wall be small, and that the gases circulate at high speed, the exchange by convection be as effective as possible taking account of course of the loss of load which results therefrom.

In order to obtain a good exchange by convection it is necessary that the fluid vein participate in this exchange throughout its whole thickness, since the gases have a slow conductive power. For that reason I circulate the gases in very thin layers (a few millimeters) and it is of interest for renewing the molecules in contact with the wall to create eddy effects by any suitable means.

The same modes of heat transmission occur in the simplified devices made according to the present process. Moreover, in a large apparatus embodying a casing having a plurality of pipes therein, the internal lining of the casing provided with outer insulating material will act as a heat radiating body or bodies towards the external row of the group of pipes.

The pipe surfaces are such that the heat transmission resulting from convection is increased by eddying of the circulating fluids, whilst the heat absorbing power and heat radiating power are as high as possible. This fact is not negligible for the heating fluid owing to the amount of steam (or vapors) and carbon dioxide which it carries with it.

To those skilled in the art it will be apparent that the inventive idea may be embodied in various forms of apparatus.

One form of such theoretical arrangement will be secured, for instance, by circulating the fluid to be heated in a pipe provided with an inner radiating core having a diameter slightly smaller than that of the pipe and providing around the pipe radiating bodies leaving around said pipe only a narrow space in which the hot fluid is made to circulate. As a variation of the same scheme the hot fluid may be circulated inside the pipe and around its inner core, while the fluid to be heated is circulated between the pipe and the surrounding body. In certain cases the same heating effect can

be secured by replacing the pipe and its inner core by a tube of small diameter or of a very flattened section.

The means of the invention, generally stated, therefore involve:

1.—Separating the fluids from each other by a thin partition wall and limiting on each side, or to one side only, the spaces provided for the passage of one or the two fluids by 10 preferably refractory and highly radiating bodies, for the purpose of:

(a) Increasing the surfaces enhancing heat transfer;

15 (b) Increasing the total useful perimeter surface of heat exchange to as great an extent as possible compared with its sectional area; that is to say securing narrow passages for the fluids;

(c) Keeping easily high the speed of circulation of each fluid.

2.—Selecting said partition wall very thin and of material as heat conductive as possible under operative conditions.

3.—Circulating one or both fluids at a 25 speed above its critical speed thus allowing the effect of convection in the thin fluid layer throughout.

4.—Increasing the length of travel of each fluid.

30 To those skilled in the art it will be apparent that the inventive idea involved may be embodied in a variety of structures, some of them being shown in the accompanying drawings and that various changes may be 35 made in the application of the same; but it is to be expressly understood that certain features may be used without other features thereof and the drawings are for the purpose of illustration only and are not designed to define the limits of the invention, 40 reference being had to the appended claims for that purpose.

In said drawings:

45 Figs. 1 and 2 are typical arrangements of flues for conducting both fluids;

Figs. 3, 4 and 5 show different forms which the flues for conducting the fluid to be heated may assume, Figs. 3 and 4 being sections taken on the lines 3—3 and 4—4 of 50 Figs. 4 and 3, respectively;

55 Fig. 6 is a central longitudinal section of a composite flue pipe designed according to the invention and provided with an interior refractory member;

Figs. 7 and 8 are central longitudinal sections of modified forms which the flues for the heating fluid and the fluid to be heated may assume;

60 Fig. 9 is a fragmentary cross-section illustrating an arrangement of the interior of a heating apparatus according to the invention;

Figs. 10 and 11 show respectively in vertical and in horizontal section, a complete

apparatus designed according to the invention;

Figs. 12 and 13 are, respectively, vertical and horizontal sections of a rotary heat exchanging apparatus according to this invention; and

Figs. 14 and 15 illustrate another form of rotary apparatus, Fig. 14 being a vertical section and Fig. 15 a horizontal section.

Referring to the drawings in which like reference numerals indicate like parts throughout the several views, and more particularly to Fig. 1, 4 and 5 are the refractory and radiating bodies limiting outwardly the passages provided for the two fluids, while 2 is the thin platewall separating the said fluids. 1 is the passage provided for the hot fluid and 3 the passage provided for the fluid to be heated. These passages are

made narrow; in other words, the distances T¹ and T³ are kept small in comparison with the section areas measured by WT¹ and WT³. Such a system insures an efficient transfer of heat. Since the partition wall 2 is thin and of material highly heat conductive, the

temperature on its face which is in contact with the fluid to be heated is very near the temperature on the other face which is in contact with the hot or heating fluid, thereby

insuring excellent conditions for heat transfer. Furthermore, the limiting radiating bodies 4 and 5 have an action particularly beneficial and increasing considerably the efficiency of the system. In the first place, the

face of the refractory body 4, looking toward the partition plate 2, offers to the contact of the hot fluid a surface about equal to that of the plate 2; this means that the refractory body 4 has the effect of approximately doubling the surface of heat absorption from the hot fluid. The heat absorbed by said refractory body 4 will afterwards be

given up by radiation to the dividing plate 2 and then transmitted to the fluid to be heated or to the other refractory body 5 which will in its turn radiate said heat and give it up to the fluid to be heated.

The refractory body 5 is therefore heated by radiation from the dividing plate 2 and afterwards transmits its stored heat to the

fluid in process of heating either by radiation or by convection. The fluid to be heated is then heated by radiation and by convection from both the partition wall 2

and the refractory body 5. It is therefore apparent that the refractory body 5, similarly to the action of body 4, has the effect of approximately doubling the surface of heat transmission to the fluid to be heated.

It is thus obvious that the scheme involves a very high efficiency of the system, as compared with that of an ordinary recuperator without the refractory radiating bodies.

It may be noted that the refractory blocks 4 and 5 are acting mostly by radiation; they

shall therefore be made of material having as much as possible a high heat radiating power under operative conditions. They may, however, be made of material more or less heat conductive, in which case they will store a certain amount of heat with more or less rapidity. For example, blocks of material having low heat conductive properties will permit, all other things being the same, 10 of the reduction of the length of time during which an apparatus must be subjected to a preliminary heating up before a continuous run is initiated.

Fig. 2 represents another typical form of 15 the invention, in which the fluid to be heated is circulated inside a pipe 2^a of small diameter or a pipe 2^b of flattened section, having preferably at the same time very thin and heat conductive walls, while the hot fluid is 20 conducted between the aforesaid pipes and refractory bodies 4^a, 4^b, in spaces 1^a, 1^b which are kept narrow.

The radiating bodies 4^a, 4^b have obviously 25 the same beneficial effect as that shown previously for block 4 of Fig. 1.

It may be observed at the same time that the flue for the fluid to be heated, here provided under the form of a pipe, could as well be constituted of two flat thin plates, as 30 plate 2 of Fig. 1, limiting the space therefrom the passage or passages for the hot fluid.

It is also obvious that the two fluids instead of being circulated in opposite directions could be conducted along the same direction, and that they could also be interchanged in their respective flues, without interfering with the beneficial effect of the 35 refractory bodies as described.

40 The two preceding examples are typical illustrations of one of the basic features of the invention, that is, the use of two radiating bodies for limiting to a narrow space on each side of a dividing wall each one of 45 the flues provided for the two fluids; or the use of two or more radiating bodies for limiting outwardly to narrow spaces the flue provided for one of the fluids, while a dividing wall encloses the other fluid in another narrow space.

50 All flues or passages being of narrow cross section, the speed of circulation of each fluid can easily be maintained above its critical velocity, for the purpose already described. The critical speed of a fluid in a conduit or passage as herein used refers to that speed or velocity which is necessary to create eddying of the fluid during its travel within said conduit or passage whereby the 55 "film" phenomenon, so deficient in heat transmission, is avoided.

In many cases it has been found practical 60 to conduct the fluid to be heated inside of flues having the character of pipes, such as 65 illustrated in Figs. 3 to 8, while these flues

are surrounded by radiating bodies such as blocks 4 of Fig. 9 for example. I will describe hereafter the character of said flue-pipes; but as already pointed out, it is to be understood that they may as well serve to 70 conduct the heating fluid, this being replaced around the flue-pipes by the fluid to be heated.

Figs. 3 and 4 show flue-pipes with outside 75 walls and inner bodies corrugated, transversely for the purpose of increasing the surfaces of heat exchange and also for the purpose of promoting eddies in one or both circulating fluids.

Fig. 5 shows a cross section of pipe-flues 80 where the passages, also kept narrow, are corrugated in the cross-section for the purpose of increasing the surfaces of heat transmission.

Fig. 6 shows a composite flue-pipe designed according to the invention and having an interior refractory member 5^a of such diameter as to leave an annular passage 3^b of narrow cross-section between the tubular member 18 and the radiating body 5^a, which 90 annular passage is open at its upper end and also at its lower end. Suspended in the lower wall of the collecting conduit 19 and surrounding the tubular member 18 is another tubular member 2 of which the inside 95 diameter is such as to leave an annular passage 3^a of narrow cross-section between said tubular members 2 and 18. These tubular members 2 and 18 are preferably very thin and highly heat conductive. The tubular 100 member 2 is closed at its lower end as shown and the annular space 3^a opens at its upper end into the conduit 19, so that the fluid to be heated is conducted as per the arrows 13 and finally collected in the conduit 19. This 105 arrangement supposes a plurality of such heating elements all attached to a common collecting conduit 19.

Referring now to Figs. 7 and 8, the flue-pipes are shown as shaped in coils preferably with thin and highly heat conductive walls, the flue 2 of Fig. 7 being simply a round pipe of small diameter. The refractory and radiating bodies 4^a and 4^b to be used in connection with this flue-pipe 110 are so spaced with relation thereto as to leave narrow passages 1 for the hot fluid, this arrangement being inspired by that of Fig. 2. The upper end of this coil is connected by any suitable or desirable joint 24 115 to the holding member 25.

Fig. 8 is in every way similar to the construction shown in Fig. 7, except that the flue 2 has its opposite side walls very close to each other, so as to leave a narrow or 120 restricted passage 3 for the fluid to be heated, thereby serving to bring more effectively all of the fluid layers passing therethrough into contact with the walls of the flue. The arrangements of the spiral 125

coils for the flues have the particular advantage that they lend themselves to the contraction and expansion resulting from the application of heat, when the other end 5 of the flues must be fastened to a second holding member similar to 25.

Fig. 9, which is a fragmentary cross-section constituting an enlargement of the arrangement employed in Fig. 11, illustrates 10 a typical arrangement of the interior of a heating apparatus constructed with pipe-flues 2 with inner refractory bodies 5 as already described. Intermediate blocks or 15 masses of refractory and radiating material 4 are interposed between the flues 2 and are so shaped and arranged as to leave narrow annular spaces 1 and other spaces 73 for the circulation of the hot fluid. As will be seen in Figs. 10 and 11, the passages 73 are 20 intended for the cross-circulation of the hot fluid. Should this hot fluid be circulated parallel to the flues 2 only, said passages 73 could be eliminated.

Figs. 10 and 11 represent a complete apparatus designed according to the invention, for instance for the purpose of heating air. 26 is a chamber having walls composed of any suitable insulating material, the nature of which may depend upon the temperature 25 to be obtained for the air, or that of the heating fluid. Said chamber is provided with two horizontal partitions 28 and 29, dividing the chamber 26 into an upper chamber 30, a lower chamber 31 and an 30 intermediate chamber 32. The cold air to be heated is admitted to the lower chamber 31 through a conduit 33, while the intermediate chamber is provided with a port 92 for the admission of hot gases and an exit 35 40 for said gases in the form of conduit 49. The heating gases may be derived from any suitable source and may be furnished by combustion of fuel gas through the port 92 with the aid of a suitable burner 34, for instance. Extending vertically within the intermediate chamber 32 is a baffle plate 36 reaching well up toward the top of said intermediate chamber. Extending from the upper side of the partition 28 to the lower 50 55 side of the partition 29 are open-ended flue-pipes 2 of a suitable type as heretofore described, with inner radiating bodies 5. Within the intermediate chamber 32 and surrounding the pipes 2 are staggered baffles 37^a, 37^b, 37^c and 37^d so arranged as to leave a circuitous path for the hot gases passing over the top of the baffle plate 36 around the pipes 2 to the exit 49 for the waste gases, all as will be clearly apparent 60 65 from the arrows 11. As already explained, 4 are intermediate blocks of radiating material, so arranged as to leave to the hot gases restricted passages 1 around the flue-pipes 2, and crosswise passages 73. These blocks 4 65 are arranged in all of that portion of the in-

termediate chamber between the partitions 28 and 29, the baffle plate 36 and the side walls of the chamber 26 that is not occupied by the tubes 2, except that on the left-hand side or inlet side, as shown in Fig. 11, some unoccupied spaces 38 are left to facilitate the entrance of the hot gases, and on the right-hand side of Fig. 11 similar spaces 39 are or may be provided to facilitate the passage of the hot gases from baffle 37^a to baffle 37^b and so on.

In the operation of the apparatus the hot gas supply is obtained from the burner 34 and from there the hot gases pass upward over the baffle 36, then follow the circuitous 80 route around the baffle plates 37^a, 37^b, 37^c and 37^d, passing through the restricted passages 1 and the other passages 73. By reason of the restricted form of passages 1, the hot gases may be passed therethrough 85 at a high velocity, equal to or exceeding their critical speed, and all of the gases will thus be enabled to come intimately in contact with the outer walls of the pipes 2 and the opposite surfaces of the radiating 90 blocks 4, whereby a large amount of heat is transferred to the blocks and the pipes; also the heat radiated from the blocks 4 and from the interior surface of the pipes 2 is transferred to the inner refractory bodies 95 5. At the same time, the air to be heated is admitted through the conduit 33 to the lower chamber 31 and passes upwardly as shown by the arrows 13 through the annular flues 3 between the interior of the pipes 2 and the radiating bodies 5, escaping into the upper chamber 30 and out through the exit port 48 provided for that purpose. Here, as in the case of the hot gases, it will be observed that the air is passed through 100 annular flues of narrow cross-section and hence can be readily moved at a velocity equal or exceeding its critical speed, whereby all the parts of the air are brought into 105 intimate relation with the interior of the heating pipes 2 and the exterior of the refractory bodies 5. As already explained, there is thus secured the very best possible condition for the transfer of heat at a 110 high rate from the hot gases to the air. With this apparatus, it is clear that the air is getting warmer and warmer as it reaches a higher level in the pipes 2, while the hot gases are cooled down more and more as they 115 reach a lower level around the same pipes 2. The tubes and accessories of the upper section are consequently hotter than the same elements of the intermediate section, these being themselves hotter than the same elements of the lower section. The advantage 120 of this arrangement is, therefore, that it is possible to make use for these several sections of pipes and their accessory equipment of materials progressively less refractory.

In order to increase the heat exchange by 130

convection I may create eddies in the heating fluid for instance by stirring the latter by rotation of the group of pipes. Figs. 12, 13, 14 and 15 show rotary heat exchanging apparatus whereby this is accomplished. Referring to Figs. 12 and 13, there is shown a rotary apparatus consisting of a stationary chamber 40 suitably supported on brackets 41. Under the chamber 40 is a rotatable chamber 42 and above the chamber 40 is another rotatable chamber 43, said chamber 42 having a partition 44 secured to and rotating therewith and said chamber 43 having a partition 45 secured thereto and likewise rotating therewith. Extending between the partitions 44 and 45 are pipes 2 affording open communication between the chambers 42 and 43. In the axis of the lower portion of the chamber 42 is a cold air inlet 46 and in the axis of the chamber 43 is a hot air outlet 47. Hot gases are admitted to the chamber 40 through the conduit 92^a, pass around the pipes 2 and take their exit through the waste gas outlet 49. The pipes 2 are provided with the interior refractory bodies and the spaces between the tubes are provided with refractor blocks as shown in Figs. 9, 10 and 11, all of those being omitted in Figs. 12 and 13 for the purpose of clearness of illustration. The chamber 42 rests upon the rollers 50, Fig. 12, and on its under side the chamber is provided with an annular rack 51 engaged by a pinion 52 driven by shaft 53 actuated by any suitable motor, not shown. When the parts are set in motion the lower chamber 42 and the upper chamber 43 together with the partitions 44 and 45 and the pipes extending therebetween are all rotated around a common axis. This prevents the high peaks of heat which would be produced in the nest of pipes and intermediate blocks around the inlet of the hot gases, if this part were stationary, with possible resultant damage to the various elements of the construction. This results from the fact that the zone of the apparatus which is subjected to the direct action of the incoming hot fluid is continuously or intermittently renewed, since it is apparent that the apparatus may be continuously or intermittently revolved, as desired. Moreover, by shifting the parts of the apparatus which receive the incoming hot fluid, the heat in that zone is greatly reduced, so that the transmission of the heat from the hot fluid in that part of the apparatus which depends upon the difference in temperature between the two is kept higher. While, as here shown, the apparatus is operated with hot gases such as waste gases for example, the same may be just as readily supplied by the combustion of fuel gas, oil or other combustible burnt in a suitable manner and introduced through the conduit 92^a. It will of course

be understood that suitable joints 54, 54, are provided between the rotating and non-rotating parts to prevent any leakage between the stationary and the revolving parts thereof. These joints may be filled for instance with water, sand, tar, molten salts, molten lead, etc., depending upon the temperature and the inside pressure involved. 70

Figs. 14 and 15 illustrate another form of rotary apparatus, especially adapted for the heating of air, for instance, to high temperature. In this form the walls of the stationary chamber 40 are supported in any suitable manner, while the parts 44, 45 and the pipes 2 extending between them revolve with the parts 42 and 43 in a manner similar to that shown in Fig. 12. In the present instance, however, the pipes 2 are arranged in a plurality of groups and are connected to plates 44 and 45; if preferred, the pipes 35 may be welded to the plates. The joints between the adjacent plates 44 and 45 are rendered tight in any suitable manner, as by use of asbestos impregnated with graphite, for example. The entire apparatus rests and revolves on rollers 50 and is driven by any suitable motor through pinion 52 and shaft 53. Within the pipes 2 are placed rods of radiating material 5 (Fig. 14), and the spaces between the pipes are filled with blocks of radiating material, not shown, constructed and arranged as previously explained in connection with Fig. 9. The cold air enters axially at the bottom through the inlet 46 and circulates upward through the annular spaces 3 between the rods 5 and pipes 2, as indicated by the arrows 13, and passes outwardly at the top as will be clearly understood by inspection of Fig. 14. The hot gases supplied by burner 55 or from any other desirable source, enter at the top of chamber 40, circulate around the several nests of tubes and the waste gases pass out through the waste pipe 49 in a manner similar to that shown in Fig. 12. Suitable joints 110 54, such as in Fig. 12, are also provided between the stationary and revolving parts. With this apparatus, it is clear that the air is getting warmer and warmer as it reaches a higher level in the pipes 2, while the hot gases are cooled down more and more as they reach a lower level around the same pipes 2. The tubes and accessories of the upper nest are consequently hotter than the same elements of the intermediate nest, these being themselves hotter than the same elements of the lower nest. The advantage of this arrangement is, therefore, that it is possible to make use for these several nests of pipes and their accessory equipment of materials progressively less refractory. The advantages of the rotation of the nests of pipes as already pointed out are lower peaks of heat with consequent safer operation, and greater efficiency in heat transmission. 130

It will be noted that a great many of the above apparatus or others which may be derived from the same invention, permit the replacement of the hot fluid by the fluid to be heated and, vice versa, the replacement of the fluid to be heated by the hot fluid, that is to say, the hot fluid may be passed through the pipe-flues as above described, while the fluid to be heated would be circulated around the same. This is but an obvious modification of the use of the apparatus, although, in principle, the efficiency is generally lower than by the application of the process as heretofore described.

In brief, the flue-pipes as hereinbefore described may be made in one or several pieces, as desirable; they may have the most various cross-sections, more or less different from a circle, especially polygonal, oval, flat sections, etc. They may also be arranged in a devious or indirect course. But in every case, the total surface or perimeter governing the heat transfer shall be as high as possible compared with the cross area of the passage left for the fluid; the thickness of their walls shall preferably be kept very small; these walls shall preferably be made of material as heat conductive as possible; the inner radiating bodies, when present, shall be constituted as explained hereafter; the fluid carried preferably circulated at a speed exceeding its critical velocity, and the length of travel of said fluid extended as much as possible. Practically, it is obvious that the above leading principles shall be combined in various degrees according to local conditions.

It is also obvious that several apparatus of the above character can be connected in series or in parallel, either to reach a given temperature or obtain a given heating capacity.

Regarding the nature of the materials to be used in the construction, it may be noted that the thin walls of the flues carrying the fluid to be heated, as heretofore described, may have to be built of various materials depending upon the temperature to which they are subjected and also the nature of the fluids coming in contact with them. It is sufficient to say that generally speaking and for temperatures comparatively low, various metals such as copper, brass, iron, steel and the like may answer the purpose, while for higher temperatures heat resisting alloys or compounds, even special refractory potteries and fused silica may be necessary. In some of the drawings, the thin walls are hatched differently from the refractory radiating bodies for purposes of illustration, but as explained above, said thin walls need not necessarily be of non-refractory material.

Since the intermediate radiating blocks and inner radiating bodies act mostly by their radiating power, it is sufficient that

both be made of material highly heat radiating under operative conditions. When these conditions are such that the intermediate blocks and inner bodies are brought to a high temperature in the scale of the luminous temperatures, the choice of the material to be used is easy because a great many materials then have a high and slightly different radiating power, also because the apparatus is fully enclosed and suitably insulated. At any rate, it may be noted that bricks and refractory potteries are generally quite satisfactory for the purpose. Said intermediate blocks and inner bodies, however, may advantageously be constituted of porous materials with the result that the radiating power is then rather higher and the heat greatly diffused. This latter fact reduces the risk of hot spots which could be detrimental to the organs. Said blocks and inner bodies may also be constituted of refractory material molded to suitable shapes, porous or not, rings, pieces of pipes of the same substances, small castings perforated or not, piled up regularly or in bulk, with or without interstices, into the spaces to be filled in or between the pipe-flues. The interstices eventually left by these assemblages, and eventually the pores of the materials, serve as passages to the fluids. This arrangement is generally favorable to obtaining a high radiating power; it is especially efficient in diffusing the heat and preventing high peaks of heat in certain zones of the apparatus.

It is indeed well known that three or four hot blast stoves are at present required per blast furnace and that the efficiency of such stoves attains only 50% to 65% notwithstanding the considerable height which is given to the apparatus, that is, the considerable length of travel which is provided for the circulation of the fluids. On the contrary, the application of the present invention permits of attaining an efficiency easily exceeding 85% and even 90%, with only one blast heating apparatus per blast furnace (or two for reason of safety), each such apparatus being much smaller than one of the present time hot blast stoves of same capacity. The smaller volume of installation of course entails smaller radiation losses which enter into account in the high efficiency observed.

While the invention has been described with considerable particularity, it is to be understood that various changes may be made in the detail of application of the same, as will be readily understood by those skilled in the art, while certain features may be used without other features thereof. Reference is therefore to be had to the appended claims for a definition of the limits of the invention.

What is claimed is:—

1. In heat exchanging apparatus of the

type operating with continuous passage of two fluids between which the heat exchange occurs, the combination of a mass of refractory bodies having multiple fluid passages, a thin flue wall of high conductive material located in said mass but with a narrow fluid passage between said flue wall and the bodies composing said mass, and a mass of refractory material within said flue 5 but with a narrow fluid passage between said inner mass and the interior wall of said flue.

2. In heat exchanging apparatus of the type operating with continuous passage of two fluids between which the heat exchange occurs, the combination of a thin walled spiral flue with refractory material within and surrounding the spiral and so spaced therefrom as to leave a passage of narrow 10 cross-section between said refractory material and the wall of said flue.

3. In heat exchanging apparatus of the type operating with continuous passage of two fluids between which the heat exchange occurs, the combination of a plurality of thin walled flues with masses of refractory material so arranged between the flues as to leave a passage of narrow cross-section between the refractory material and the flues, 15 said masses of refractory material being provided with a multiplicity of restricted passages through or within the same for the fluid.

4. In heat exchanging apparatus of the type operating with continuous passage of two fluids between which the heat exchange occurs, the combination of a plurality of flues for conducting one of the fluids with masses of refractory porous material in the 20 spaces intermediate said flues and surrounding the latter but spaced slightly therefrom to provide narrow passages for the other fluid.

5. In heat exchanging apparatus of the type operating with continuous passage of two fluids between which the heat exchange occurs, two adjacent flues each having a wall of heat-radiating refractory material, and a partition of thin, heat-conducting material forming one of the walls of each flue. 25

6. In heat exchanging apparatus of the type operating with continuous and simultaneous passage of two fluids between which the heat exchange occurs, the combination of a wall, preferably very thin and highly heat conductive under operative conditions, for separating the two fluids, and of adjacent radiating bodies otherwise limiting on each side of said wall the flues provided for 30 the two fluids, whereby the heat imparted to the fluid to be heated comes partly from a direct exchange of heat through the separating wall, partly from the heat radiated by one of the radiating bodies, and partly from 35 the heat radiated by the same body which

is then absorbed and afterwards radiated or given up by the second radiating body.

7. In heat exchanging apparatus of the type operating with continuous and simultaneous passage of two fluids between which the heat exchange occurs, the combination of a flue with walls preferably very thin and highly heat conductive under operative conditions, of an inner body, preferably made of material highly heat radiating under operative conditions, whereby there is obtained between said flue and inner body a narrow passage for one of the fluids, and of another body, preferably made of material highly heat radiating under operative 70 conditions, surrounding said flue and so spaced therefrom as to leave therebetween a narrow passage for the second fluid.

8. In heat exchanging apparatus of the type operating with continuous and simultaneous passage of two fluids between which the heat exchange occurs, the combination of a spiral flue, having a wall preferably very thin and highly heat conductive under operative conditions, with a refractory material, preferably highly heat radiating under operative conditions, within said flue and surrounding the spiral and so spaced therefrom as to leave a passage of narrow 80 cross-section for one of the fluids, between 85 said refractory material and the wall of said flue.

9. In heat exchanging apparatus of the type operating with continuous and simultaneous passage of two fluids between which the heat exchange occurs, the combination of a spiral flue, having preferably a small cross-section, and walls very thin and highly heat conductive under operative conditions, with a refractory material, preferably highly heat radiating under operative conditions, surrounding said flue and so spaced therefrom as to leave a passage of narrow cross-section for one of the fluids between said 90 refractory material and the walls of said flue.

10. In heat exchanging apparatus of the type operating with continuous and simultaneous passage of two fluids between which the heat exchange occurs, the combination of a plurality of concentric tubular members, having preferably walls very thin and highly heat conductive, with an inner refractory body inserted in the smallest tubular member, whereby there is obtained therebetween a plurality of passages, preferably very narrow, through which one of the fluids is conducted successively and along directions successively reversed, the largest of the said tubular members being surrounded with a radiating body coming in close proximity therewith, so as to leave a narrow passage or narrow passages for the second fluid between said largest tubular member and surrounding body. 115 120 125 130

11. The method of securing exchange of heat between two fluids, which consists in moving said fluids separately, on opposite sides of a thin highly refractory conductive and radiating partition, one of said fluids being moved at high speed and in a thin layer between said partition and a closely arranged facing body of highly refractive and radiating material, and simultaneously developing turbulence in said fluids, whereby heat exchange is secured between the two bodies by the simultaneous action of conduction, radiation and convection.

12. In an apparatus for securing exchange of heat between two fluids, the combination of two conduits for the two fluids having a common wall of thin highly conductive and radiating material and outer walls of refractory radiating material, whereby simultaneous intensified heat exchange by conduction, radiation and convection is secured between the two fluids, said conduits being formed to create eddies in the fluids passing therethrough.

13. The method for effecting transfer of heat from a heating gas to a gas to be heated through the medium of a diaphragm which comprises transferring heat by convection from the heating gas to the diaphragm, thence by conduction through the diaphragm, thence directly by convection to the gas to be heated and indirectly by radiation to a heat absorbing body positioned in the path of the gas to be heated and by convection from the surface of said body to said gas.

14. The method for effecting transfer of heat between a heating gas and a gas to be heated through the medium of a diaphragm which comprises transferring heat from the heating gas directly by convection to the diaphragm and indirectly, by convection to a heat absorbing and heat radiating body positioned in the path of the gas and thence by radiation to the diaphragm, passing heat thus transferred, by conduction through the diaphragm, and transferring such heat from the surface of the diaphragm directly by convection to the gas to be heated and indirectly by radiation to a heat absorbing body positioned in the path of the gas to be heated and thence by convection from the surface of such body to said gas.

15. The method of effecting heat transfer between a moving body of hot gas and a moving body of cold gas through the medium of a diaphragm which comprises transferring heat by convection from the hot gas to the diaphragm thence by conduction through the diaphragm, and thence by radiation to a heat absorbing body and by convection from said body to the cold gas.

16. The method for effecting transfer of heat from a moving body of hot gas to a moving body of cold gas through the me-

dium of a diaphragm which comprises transferring heat carried by the hot gas by convection to a heat-absorbing body and thence by radiation to the diaphragm, thence by conduction through the diaphragm, and thence by radiation to a heat absorbing body and by convection from said last named body to the cold gas.

17. The method for effecting heat transfer between a heating gas and a gas to be heated which comprises absorbing heat from said heating gas transmitting heat thus absorbed to one side of a heat conductant diaphragm by radiation, thence by conduction through the diaphragm, thence directly by convection to the gas to be heated and indirectly by radiation to a heat absorbing body positioned in the path of the gas to be heated and by convection from the surface of said body to said gas.

18. The method of effecting efficient transfer of heat from a gaseous heating body to a gaseous body taking up heat through the medium of a metal diaphragm which comprises transferring heat from the heating gas to the metal, placing a refractory body having relatively large bulk and surface area in the path of the gas taking up heat to absorb heat radiated from the metal and to transmit it by convection to the gas, and utilizing the heat storage capacity of the refractory to continuously furnish heat to the gas during intervals in which the volume of heat radiated from the metal is reduced.

19. Apparatus for effecting transfer of heat from a heating gas to a gas to be heated through the medium of heat conducting walls which comprises a housing, partition walls of heat conducting material extending therethrough, means for passing gas to be heated along one surface of said walls and out of contact with heating gas passing along the opposite side of said walls, bodies of refractory material positioned in the path of the heating gases facing and spaced from the surface of the heat conducting walls, and other bodies of refractory material in the path of the gas to be heated and facing and spaced from the opposite surface of the walls.

20. Apparatus for effecting transfer of heat from a heating gas to a gas to be heated through the medium of metal walls which comprises a housing, metal conduits extending therethrough and arranged to keep gas to be heated out of contact with heating gas, means for passing gas to be heated through the conduits, means for passing heating gas through the housing in contact with the outer surface of the conduits, and cores of refractory inside the conduits having relatively large heat absorbing and heating surfaces facing and spaced from the inner surface of the conduit.

21. Apparatus for effecting transfer of heat from a heating gas to a gas to be heated through a medium of metal walls which comprises a housing, a plurality of metal conduits extending longitudinally therethrough, means for passing a heating gas in contact with the outer surface of said conduits and means for passing a gas to be heated through said conduits, and cores of relatively bulky refractory having a substantial heat storage capacity in said conduits with a relatively large heat absorbing surface facing and spaced from the inner wall of the conduit to absorb heat radiated from the metal wall and to supply heat continuously to gas flowing between the outer surface of the core and the inner surface of the metal.

22. Apparatus for exchange of heat between two fluids moving separately on each side of a thin partition, one fluid at least being circulated at high speed and in a thin

layer between the partition and a closely adjacent facing body, the partition and facing body being made of materials highly refractory and radiating whereby continuous and simultaneous intensified heat exchange is effected by conduction, radiation and convection, said thin partitions comprising spiral tubes of small diameters in which and around which are arranged the refractory bodies.

23. In a method for the exchange of heat between two fluids according to claim 12, the step of imparting additional turbulence to one fluid to increase heat transfer resulting from convection by moving the flues in which the other fluid circulates.

24. In an apparatus according to claim 13, means for moving one of said conduits whereby turbulence is imparted to one of the fluids and the heat exchange resulting from convection is increased.
